TUBING RELEASE VALVE.

Application filed May 5, 1924. Serial No. 711,182.

This invention is an outlet valve construction for pump tubing, flow pipes, and the like.

An object is to make a construction to be incorporated into a pump tubing above the pump mechanism so that when it is desired to pull the pump tubing and pump, the valve may be opened to allow the contents of the pump tubing to run downwardly and out.

10 Other objects and advantages will appear from the drawings and specification.

The drawings illustrate an outlet valve construction for pump tubing embodying the principles of our invention.

15 Figure 1 is a side elevation looking in the direction indicated by the arrow 1 in Fig. 2, the pump tubing being broken away above and below the outlet valve construction.

Fig. 2 is a vertical diametrical sectional detail on the lines 2—2 of Figs. 1, 3 and 5, including the well casing, and parts being omitted in Figs. 3 and 5.

Fig. 3 is a horizontal section on the line 3—3 of Fig. 2 and showing the valve closed.

25 Fig. 4 is a view analogous to Fig. 3 and showing the valve open.

Fig. 5 is a horizontal section on the line 5—5 of Fig. 2.

The details of the outlet valve construction for pump tubing shown in the drawings are as follows:

30 The section of pump tubing 1 is preferably located above the pump cylinder and plunger mechanism and may be any of the usual sizes. A valve casing 2 is clamped upon the pump tubing 1 and is formed in two pieces 3 and 4 meeting upon the longitudinal diametrical lines 5 and clamped together by bolts 6 and fitting rotatably upon

40 the pump tubing 1. An annular chamber 7 is formed horizontally in the casing 2 around the tubing 1, the vertical wall 8 of the chamber being eccentric to the tubing 1 and there being outlets 9 through the wall 8. A valve seat member 10 is tapped through one wall of the tubing 1 and has a valve seat 11 upon its inner end. The outer end of the member 10 is closed by a flange 12 and openings 13 are formed laterally inside of the valve 12.

45 50 A valve head 14 fits the seat 11 and has a stem 15 extending through the flange 12. A spring seat 16 is fixed upon the outer end of the stem 15 and an expansive coil spring

17 is mounted upon the stem 15 between the seat 16 and the flange 12, the tension of the 55 spring being exerted to hold the valve 14 closed.

When the pump tubing 1 is turned so that the valve stem 15 is at the greatest width of the chamber 7 between the wall 8 and the 60 tubing 1, as in Fig. 3, the stem 15 is short as required to allow the valve head 14 to seat, and when the pump tubing 1 is rotated in the casing 2, the outer end of the valve stem 15 bears against the inner face of the 65 wall 8 and forces the valve 14 away from the seat 11 as shown in Fig. 4.

An annular chamber 18 is formed in the casing 2 around the tubing 1 and a pin 19 is fixed through the tubing 1 and extends into the chamber 18 to hold the casing 2 from moving longitudinally upon the tubing 1. Stops 20 and 21 are formed in the chamber 18 to limit the rotation of the tubing 1 in the casing 2 to a half a turn back and forth, 75 as shown in Fig. 5.

Sockets 22 and 23 are formed at one side of the casing 2 and similar sockets 24 and 25 are formed at the other side. The bowed leaf spring 26 is mounted with its ends in 80 the sockets 22 and 23 and the ends of the spring are bent to form hooks 27 and 28, and pins 29 and 30 are mounted through the walls of the sockets and loosely through the hooks to hold the spring in place and allow 85

the ends to slide. A guide pin 31 is fixed through the center of the spring and an expansion coil spring 32 is mounted upon the pin 31 and against the casing 2, the tension of the spring 32 being exerted to force the 90 center of the spring 26 outwardly. In a like manner, the bowed leaf spring 33 fits in the sockets 24 and 25 and has hooks 34 and 35, and pins 36 and 37 are inserted through the side walls of the sockets and 95 through the hooks to hold the spring in place, and a pin 38 extends inwardly from the center of the spring 33, and an expansion coil spring 39 is mounted upon the pin 38 against the side of the casing 2.

100 Knobs 40 and 41 extend from the casing 2 into the inner ends of the springs 32 and 39.

When the outlet valve construction has been placed upon and incorporated into the tubing 1 and the tubing is lowered into the well casing 42, the springs 26 and 33 are 105

contracted and placed under tension and form runners to slide down the casing 42, and when the pump tubing 1 has been set the tensions of the springs 26 and 33 and 32 and 39 will be sufficient to hold the valve casing 2 from rotating in the well casing 42 so that by manipulating the upper end of the pump tubing 1, the tubing may be turned to bring the pin 19 into engagement with the stop 21 and the valve 14 is closed so that the pump may operate to raise liquid upwardly through the tubing 1 and when the pump mechanism becomes clogged or worn and it is desired to raise the pump tubing 1, the upper end of the pump tubing 1 may be manipulated to turn the pin 19 backwardly to engage the stop 20, and the valve 14 will be opened to allow the contents of the pump tubing 1 to run out through the ports 9 as the pump tubing is raised, thereby avoiding the necessity of lifting the load within the pump tubing and avoiding the nuisance due to handling the pump tubing loaded with oil and the like, as the sections of tubing are disconnected at the upper end.

The outlet valve construction may be advantageously used near the lower ends of flow pipes so that when the well becomes sanded and the lower end of the flow pipe clogged and it is desired to remove the flow pipe, the contents of the flow pipe may be discharged through the outlet valve construction.

35 Heretofore, when it became necessary to pull a pump tubing, it has been usual to raise the pump tubing a hundred feet or more up into the derrick and unscrew it at the casing head and the oil in the hundred feet of tubing runs out at the point of disconnection and runs all over the derrick floor and wastes the oil and every once in a while catches fire and burns the rig up.

Various changes may be made without departing from the spirit of our invention as claimed.

We claim:

1. A tube adapted to be incorporated into a well string, an inwardly opening valve mounted through the wall of the tube and spring pressed closed, a valve casing relatively rotatably mounted upon the tube to open the valve, and springs carried by the valve casing to engage a well casing and hold the valve casing while the tube is rotated.

2. An outlet valve construction comprising an eccentric valve casing, a tube rotatably mounted in the valve casing, means for holding the casing against rotation in a well casing, and an inwardly opening self-closing valve mounted through the wall of the tube in position to be engaged and opened by the casing.

3. An outlet valve construction comprising a casing, a tube rotatably mounted in the casing and held against endwise movement in the casing, means for holding the casing against rotation in a well, an inwardly opening self-closing valve mounted through the wall of the tube, and means whereby rotation of the tube opens the valve.

4. The combination with a pump tube or the like, of an outlet valve construction mounted upon the tube and adapted to be held against rotation in a well, and having means whereby rotation of the tube opens the valve to empty the tube.

5. The combination with a pump tube having a pump and an outlet formed in the tube above the pump, of a valve adapted to close the outlet, spring means urging the valve into closed position, a member carrying friction springs engageable upon the interior of a well casing movably mounted upon the tube, said member presenting an irregular surface, said valve having a stem engaging said surface whereby when the tube is moved, the member will be frictionally held stationary so that the valve may be opened or closed because of the engagement between the stem and said irregular surface.

6. The combination with a pump tube having a pump, of an outlet valve construction mounted upon the tube above the pump, and means mounted about the tube engageable upon the interior of the casing so as to be retained against rotation therein, said means being so arranged and so associated with said valve that when the tube is rotated the valve will be actuated.

7. In combination with a pump tube, means providing a port through the tube, a valve adapted to close said port, spring means for urging said valve into closed position, and means engageable upon the interior of the casing associated with said valve, whereby when the tube is rotated within the well, said valve may be forced open.

8. In combination with a pump tube, means providing a port through the tube, a valve adapted to close said port, spring means for urging said valve into a predetermined position, and means associated with the valve adapted to be frictionally held within the well casing, whereby when the tube is rotated within the well casing, said valve may be moved from its predetermined position.

9. In combination with a pump tube, means providing a port in the pump tube, a spring closed valve having an outwardly extending stem adapted to close said port, a casing presenting an eccentric interior surface engageable by the valve stem rotatably mounted about the tube, and means carried by the casing engageable upon the interior of the well casing for resisting rotation of

said casing within the well casing, whereby upon rotation of the tube, said valve may be moved to open position.

10. In combination with a pump tube, means providing a port in the pump tube, a spring closed valve having an outwardly extending stem adapted to close said port, a casing presenting an eccentric interior surface engageable by the valve stem rotatably mounted about the tube, means carried by the casing engageable upon the interior of the well casing for resisting rotation of said casing within the well casing, whereby upon rotation of the tube, said valve may be moved to open position, and means preventing axial movement of the casing upon the tube.

11. In combination with a pump tube, means providing a port in the pump tube, a spring closed valve having an outwardly extending stem adapted to close said port, a casing presenting an eccentric interior surface engageable by the valve stem rotatably mounted about the tube, means carried by the casing engageable upon the interior of the well casing for resisting rotation of said casing within the well casing, whereby upon rotation of the tube, said valve may be moved to open position, and means for limiting rotation of the tube within the casing.

- 30 12. The combination with a pump tube having a pump of means carried by the pump tube engageable upon the interior of a well casing so as to be held against rotation therein, a means operable by rotatably moving the pump tube relatively to said means for opening an outlet from the tube above the pump, permitting the tube to be drained.

- 35 13. The combination with a pump tube having a pump of friction springs carried by the pump tube above the pump adapted

to be held against rotation in a well, a means operable by rotating the pump tube relatively to the friction springs for opening an outlet from the tube above the pump, permitting the tube to be drained.

- 45 14. In combination with a pump tube having a pump, means carried by the pump tube above the pump capable of rotatably moving relatively thereto, said means being engageable upon the interior of a well casing so as to be frictionally held against rotation relatively to the casing, a means operable by rotatably moving the pump tube relatively to said means for opening an outlet from the pump tube above the pump, permitting the 50 55 pump tube to be drained.

15. In combination with a pump tube having a pump, means operable by rotating the pump tube for opening an outlet from the tube above the pump, permitting the tube to 60 be drained.

16. The combination with a pump tube having a pump of means operable by rotatably moving the pump tube and the pump for opening an outlet from the tube above 65 the pump, permitting the tube to be drained.

17. In combination with a pump tube having a pump, means carried by the pump tube engageable upon the interior of a well casing and adapted to be frictionally held thereby against rotation, and means operable by rotatably moving the pump tube and the pump relatively to said means for opening an outlet from the tube above the pump, permitting the tube to be drained.

In testimony whereof we have signed our names to this specification.
